UNITED STATES PATENT OFFICE

2,587,811

MECHANICAL CLOTH-LAYING APPARATUS

Abraham Bieber, Liverpool, England, assignor to
Express Patent Company (Liverpool) Limited,
Liverpool, England, a company of Great Britain

Application August 4, 1947, Serial No. 766,008
In Great Britain September 1, 1939

Section 1, Public Law 690, August 8, 1946
Patent expires September 1, 1959

3 Claims. (Cl. 270—31)

1

This invention relates to cloth laying machines as used in the cutting rooms of clothing factories where it is desired to cut a plurality of superimposed layers of cloth simultaneously.

My invention aims to produce a machine or apparatus for the purpose specified, which is simple in construction and so cheap to manufacture, easily manipulated, certain in action not liable to derangement under working conditions, and which obviates necessity for the lifting of heavy weights of cloth by the operator as has heretofore been essential in machines in connection with which the cloth supply is placed by and upon a reciprocable carriage situated above the table and adapted for hand actuation.

It is a feature of my invention that although the cloth is layered by the aid of a guide carrier having to-and-fro movement over a table, such cloth (in roll or other form as received from the cloth manufacturers) may be supported upon a room floor or a low platform or table or in a roller-cradle resting upon the floor.

A cloth laying machine according to my invention includes a table; a carrier reciprocably mounted on rails provided at each side of the table, opposed pairs of cloth holders mounted on and near each side of the table and at a preset distance between same, each holder comprising a pivotal lifting bar and a cloth holder proper pivotally mounted to the free end of said lifting bar; means between said carrier and opposed pairs of lifting bars and cloth holders for actuating the same so that said cloth holders proper are released and engaged from and with the cloth in the reciprocable travel of said carrier over the table; locking means arranged to hold said cloth holders proper at right angles to their respective lifting bars when in cloth-engaging position; the arrangement being such that said cloth holders when in their cloth-disengaging position comprise forward extensions of said lifting bars and do not move outwardly beyond the sides of the table top.

Other features appertaining to this invention are hereinafter described and illustrated with reference to the accompanying drawings these features being within the scope of the appended claims.

I will further describe my invention with the aid of the accompanying sheets of explanatory drawings which illustrate, by way of example only, one mode of carrying the invention into effect.

In said drawings:

Figs. 1A and 1B are together a side elevation in part section, and

2

Figs. 2A and 2B are together a plan view of a cloth laying machine constructed in accordance with my invention, the sectional part of Figs. 1A, 1B being taken on the line A—A, Figs. 2A, 2B.

Fig. 3 is an enlarged detail of the cloth holders shown in Fig. 2A.

Fig. 4 is a fragmentary cross-section taken on line B—B, Fig. 1A.

In the several views like characters of reference denote like or equivalent parts wherever they occur.

Referring to the drawings, 1 designates a table top, say of wood or metal, which, in the operation of the machine, is of constant height, there being no necessity for its vertical adjustment during use. On said table top 1 is reciprocably disposed a cloth-layering guide carrier, generally designated 2, which includes side members or cheeks 3, 4 spacedly and rigidly connected by suitable distance rods such as those shown at 5, 6, 7 and 8, each side member 3, 4 having a pair of flanged wheels or rollers 9, 9a revoluble on ball bearings and adapted to run on rails 10 longitudinally disposed one at each side of the table top 1, but so that the outer edge of each rail base portion projects—as shown in Fig. 4—somewhat from an angled frame member 11 of the table whereto legs 12 are secured. Said rails 10 are also secured to said angled frame members 11.

Between upper extensions 3a, 4a, of said side members 3, 4 a roller 13 is journaled, and below same are a pair of spaced rollers 14, 15 journaled between brackets 16 secured to the underside of a transverse angle iron 17 which has its opposite ends respectively secured to vertically disposed members 18 of T-section slidably mounted in guides 19 formed one at the inner face of each of the carrier side members 3, 4. Edge portions of each of the vertically slidable members 18 are formed with ratchet teeth 18a which are respectively engaged by pawls 20 mounted on, so as to turn with, a transverse rod 21 rotatably carried by the carrier side members 3, 4. Said pawls 20 normally tend to engage the ratchet teeth 18a under the influence of coiled springs 22.

Said double roller carrying assembly 14 to 18, inclusive, is adapted to be raised and lowered from a side of the machine by the aid of a hand lever 23 which turns a transverse rod 24 carrying crank arms 25 actuating links 26 pivotally anchored at their lower ends to a side of angle iron 17, so that the two spaced rollers 14, 15 may be gradually raised as the thickness of the cloth layers increases during the operation of the machine as hereinafter described.

Alternatively, it may be arranged that said

spaced roller assembly 14 to 18 shall be self-raising and automatically held as the cloth layering process proceeds.

To lower said vertical ratchet members 18 and so their associated rollers, 14, 15 towards the table top 1 again, said pawls 20 may be simultaneously disengaged from the ratchet teeth 18a by means of a handle 27 secured to the pawl-carrying rod 21, the lowering movement of the lower roller assembly 14 to 18, under gravity, being controlled by the hand lever 23 actuating the crank arms 25 and links 26.

Secured to the inner faces of each side member 3, 4 are brackets (not shown) on the underside of which are secured rubber buffers 28, the purpose of which being later described.

Situated on and near the sides of the table top 1 and at desired longitudinal and pre-set distance between same, i. e. according to the length of the cloth layers to be made, are pairs (two pairs in all) of similar appliances one of which I will now describe, reference being particularly directed to Fig. 3.

Revolutely mounted by its rear end on a rod or shaft 29 rotatably journalled in bearings 30 secured to the table and transversely spanning the table top 1 at a suitable height above same and being counter-balanced by a tension spring such as 31 (or weight) is a longitudinally arranged bar 32 (hereinafter for convenience of reference designated "lifting bar") whereon, near its free (front) end, a second blade-like bar 33 (hereinafter for convenience of reference, designated "cloth holder") is pivoted as shown at 34, said cloth holder 33 being normally locked in a position at right angles to said lifting bar 32. Nearer to the rear end of said lifting bar 32 there is pivoted thereon a cross bar or lever 35 on one side of its fulcrum 36 is pivotally attached at 37a an end of a connecting rod 37 the other end whereof is connected at 37b with said cloth holder 33. If desired, said connecting rod 37 may be duplicated, i. e. a second rod being anchored between lever 35 and cloth holder 33, the points of pivoting of said second bar being at the other side of the pivots 34, 36.

Pivoted on said cross lever 35 is a locking lever 38 one end whereof is formed into a catch-like recess tending under influence of compression spring 38b to engage a cooperating catch block 39 adjustably mounted on the lifting bar 32, and in its normal position does so engage. Said block 39 is adjustable in a housing 40 by means of a screw 41.

A tension spring 42 anchored between the inner end of cross lever 35 and rod 29 tends to maintain said cloth holder 33 (against opposed adjustable stops 43 carried at the free end of the lifting bar 32) in said requisite position at right angles to the lifting bar, and the outer end 38a of locking lever 38, as also a coincident outer portion of cross lever 35, projects into the path of reciprocal travel of an oscillatable arm 44 pivotally suspended from said guide carrier 2 for the purpose later described. Said lifting bar 32 is also provided with a rigid upwardly inclined tongue 32a which turns as one with the lifting bar 32 and rod 29 together with a hub member 32b keyed to rod 29 and whereto lifting bar 32 is secured. Said tongues 32a are adapted to cooperate with the outer distance rods, 5, 8 of the carrier 2, as later described, for the purpose of raising the lifting bars 32, such raising movement being determined by the inclination of tongues 32a.

In initial position for cloth layering, each lifting bar 32 lies with its front end, which has a rubber foot piece 45, resting on the table 1, and the cloth holder 33 (now locked) is lying horizontally on and at right angles to said lifting bar near its free front end. The cross lever 35 on said lifting bar 32 is also at right angles thereto with its locking lever 38 engaging under spring pressure, the cooperating catch block 39 on the lifting bar. Thus said cloth holder 33, for the time being, is immovable.

The operator of the machine moves the carrier 2 by means of a side handle 2a and in a stroke of the guide carrier over the table say in the direction of the arrow E, Figs. 1A and 1B, said oscillatable arm 44 which has pivotal freedom of movement in one—its forward—direction only, it being in abutment against an adjustable stop 46, engages with and moves the part 38a of said spring-influenced locking lever 38 lying in its path and in so doing unlocks this lever from catch block 39. Said oscillatable arm 44 also engages with the cross lever 35 and turns same about its pivot 36 so that in the further travel of the carrier 2 the (now-freed) cloth holder 33 is moved to a longitudinal position (i. e. in alignment with the lifting bar 32 as shown in dotted lines Fig. 2A) through the consequential actuation of the connecting rod 37, and against the resistance of spring 42. In this movement of the cloth holder 33 during a layering operation the inner portion thereof is moved clear of the cloth x on the table, and on the continued stroke of the guide carrier 2 the distance rod 5 of the latter engages said tongue projection 32a of the lifting bar 32, thus the forward end of the same with cloth holder 33 is raised in the turning of rod 29, such raising movement being substantially assisted by the counterbalancing spring 31.

On the continued travel of the guide carrier 2, said swinging arm 44 passes beyond cross lever 35 and releases it when the catch lever 38 moves to its normal locked position again, so that the inner portion of the cloth holder 33 is above the then top layer of cloth, this movement being effected by said connecting rod 37 and tension spring 42 associated with the cross lever 35. Thus, cross lever 35 now lies again across the lifting bar 32 in locked condition and the cloth holder 33 rests in locked condition at right angles to the lifting bar 32 on the uppermost layer of cloth, to form a stop and enable another cloth layer to be formed on the reverse stroke of the guide carrier 2.

The stroke of the carrier 2 is restricted through the rubber buffers 28 abutting against the upper faces of the pair of lifting bars 32. Thus, the buffers 28 also restrict the raising movement of bars 32.

The guide carrier 2 is now drawn away by its handle 2a for its next stroke on the table in which motion the swinging rod 44 retires, passing over the cross and locking levers 35, 38 and the operation is repeated with the other pair of cloth holders 33 to form another and so on.

In order to minimise disturbance of the cloth x as and when the pairs of holders 33 are being released from the cloth, the top and underside of each holder 33 are formed with spaced rib-like projections 33a curved concentrically with the axis 34 about which holder 33 pivots.

Prior to the layering process, the longitudinal setting of one pair (i. e. the left hand pair as shown in the drawings) of folding devices having been effected to suit the length of cloth layers

required, the free end of the cloth to be layered is led over a guide roller 47 journalled in the bearings 30 at the rear end of the table, over the upper roller 13 of the reciprocable guide carrier 2, between and under the spaced lower rollers 14, 15 of the carrier and conveniently secured to the table top, as by means of a gripping bar 48 and chain link 49 shown in Fig. 2B so that when the guide carrier 2 is moved along the table by handle 2a it pulls the cloth with it and as the folding devices 32, 33 are operated as before described, on each stroke of the guide carrier the approached pair of cloth holders 33 move out of the uppermost cloth fold, rise, inwardly return and drop onto the face of the then uppermost cloth layer to provide a stop to enable the formation of the next succeeding fold. In no circumstances, however, do the cloth holders 33 move laterally or outwardly beyond the sides of the table top 1.

The free ends of the cloth holders 33 of a pair may be situated close together when in operative position, i. e. at right angles to their lifting bars 32 so that cloth of varying widths may be folded and this without necessity for any lateral adjustment of the bars 32 on the rod 29.

For the laying up of light materials, I may position on the table a device shown diagrammatically at G. Fig. 2A, having upper and lower gripping jaws adapted to be operated by the carrier 2 in order to hold the folded cloth, whilst the holders 33 are straightening out to their cloth-disengaged position.

Any suitable guide device or devices, such as the adjustable collars 50, may be associated with the rollers 13, 47 to ensure the prevention of lateral displacement of the cloth in the folding operations, as also slideable guides 51 (to guide the cloth over roller 15) mounted on a bar 52 secured to transverse angle iron 17, whilst other adjustable components may be fitted as desired to provide for the layering of cloths of varying widths. Further, a spring-pressed brake device 53 actuated by wing nut 54 may be provided to restrict the rotatable freedom of movement of roller 13 with a view to maintaining the cloth taut if so desired, and in this connection the roller 14 may be similarly restricted or locked against rotary movement.

To adjustably connect the movable, i. e. the left hand pair of layer devices 32, 33 to the table the rotatable rod 29 on which the ends of the pair of lifting bars 32 are secured is mounted on brackets 30 secured to one of a pair of transverse bars 55 which are connected by metal plate members 56 having depending portions 56a which slidably engage with the vertical component of the rails 10. Provided between said bars 55 is a transversely disposed channel guide 57 and slidably located therein is a bar 59 having at one end a shoe 60 adapted to bear on one side of the table. The other end of bar 59 is provided with a screw threaded rod end 59a, and carries, on an extension 58a, a shoe 58 adapted to bear on the other side of the table. A nut lever 61 is provided on rod end 59a, and on turning said nut lever in the appropriate direction both shoes 58, 60 which lie below said projection part of the base of the rails 10 are tightened up or slackened as desired.

In order to lock the carrier 2 to the adjustable clamp assembly just described a pair of hook members 62 connected together by a rod 63 are pivotally connected with a rod 29, the hooked members 62 being adapted to engage with the dis-

tance rod 5 of the carrier when the latter is at this end of the table, thus the carrier may be readily locked to this assembly when adjustment of the left hand pair of cloth holders is being effected by movement of the carrier 2.

In order to temporarily raise said pairs of cloth holders 32, 33 clear of the table top when it may be required to use, the surface of the table, the left hand pair of cloth holders 32, 33 are raised and held by a hook 64 which engages with a pin 65 connected to one of the tongues 32a of a lifting bar. The right hand pair of cloth holders 32, 33 may be similarly raised and temporarily held in such out of use position by a transverse rod 66 being placed across U-shaped bearings formed at the upper ends of brackets 30 and under which the inclined arms 32a of the respective cloth holders abut. Said bar 66 which also serves as a guide for the cloth passing over roller 47 is removed when it is required to lower the cloth holders on to the table.

The machine is provided with a low platform or table 67 whereon cloth laid in flat layers may be fed over roller 47 to the machine as shown by the dotted line x¹ but for dealing with cloth in flat roll form with a cardboard or other stiffening insert through the middle, as shown at x² Fig. 1, I provide a pair of uprights 68 which are adjustable upon a horizontal bar 69 secured to the low platform or table 67. The upper ends of said uprights 68 constitute bearings for shafts or spindles 70 each of which carries a shaped holder frame 71 on which an end of a cloth roll may be mounted, so that when tension is imposed on the cloth in the layering operation the roll x² of cloth will readily revolve to permit of the loose or free end of the cloth being pulled away. A hand wheel or handle 72 secured to one of said shafts 70 permits the cloth roll x² to be rewound if desired.

For the handling of cloth rolled upon tubes of cardboard or the like, said shafts or spindles 70 mounted in the bearings of said uprights 68 may have, at the ends remote from the holding means 71 already described, tapering or conical members 73 adapted to project into the ends of and carry a tube. Said conical carrier member 73 may be brought into confronting position for use by reversing the uprights 68 which may be secured in adjusted position by means of a wing screw 74 which passes through an apertured base 75 of the upright 68 and which base 75 is slidably mounted by rollers 76 on said horizontal bar 69. A lay or guide edge piece 77 (Fig. 1B) for the cloth when placed flat upon said platform 67 may be positioned when adjusted by means of a wing-screw passed through a depending extension of an angle metal strip (not shown) to which the guide or lay board 77 is secured, and bearing on the horizontal bar 69.

For the handling of light material such, for example, as silks rolled on a rigid rod or tube, I may provide a pair of brackets 78 each secured to a side of the cloth-roll-supporting uprights 68, each bracket 78 carrying a pair of spaced roller wheels 79 whereon ends of said rigid rod or tube which project from the material wound thereon rest so as to readily roll when the material is passed over said guide roller 47 and pulled by actuation of the carrier 2 as before described; or, alternatively, said roll of light material may be suspended between similar brackets 80 carrying spaced roller wheels 81 secured to the upper extensions 3a, 4a of the carrier side members 3, 4.

What I claim as my invention and desire to secure by Letters Patent is:

1. A cloth laying machine comprising in combination a table provided with rails at its opposed sides, a carrier reciprocably mounted on said rails, rotatable rods journalled in bearings arranged at side of said table, contacting tongues provided on each of said rotatable rods, two opposed pairs of cloth holders and each pair being mounted on a rotatable rod in a pre-set distance apart, each cloth holder comprising a lifting bar secured at one end to its respective rod, a cloth holder proper pivotally mounted on the opposite or free end of said lifting bar, stops on said lifting bar for limiting movement of said cloth holder proper, a lever pivoted to said lifting bar, a connecting rod pivotally attached to the inner end of said lever and to said cloth holder proper, a second locking lever pivoted on the outer end of said first-mentioned lever and having a catch-like recess formed in one end, a compression spring between said first-mentioned lever and said locking lever for causing engagement of the catch-like recess of said locking lever with a co-operating catch block mounted on the lifting bar, a tension spring connecting the inner end of said first lever with the rotatable rod, pendant arms provided on said reciprocable carrier for contacting and releasing said locking lever and moving said cloth holders proper from cloth engaging position at right angles to said lifting bar to a cloth disengaging position wherein they form extensions of said lifting bars, and means on said reciprocable carrier for contacting said tongues provided on said rotatable rods for raising said lifting bars after the cloth holders have moved to cloth disengaging position.

2. A cloth laying machine as claimed in claim 1, wherein said carrier comprises a pair of connected side members having upper extensions, flanged wheels revolvably secured to said side members adapted to run on said rails of the table, a roller journalled between said side members' upper extensions, brackets secured on the underside of a transverse bar the ends of which latter are affixed to vertical members mounted in guides formed one at the inner face of each carrier side member, a pair of spaced rollers journalled between said brackets, ratchet teeth on said vertical members, a rod rotatably supported by the carrier's side members, pawls secured adjacent the ends of said rod and engageable with said ratchet teeth, springs between said pawls and the adjacent carrier's side members for engaging the pawls with the ratchet teeth of

5

said vertical members, a hand lever for raising said spaced rollers and secured to a transverse rod journalled between the carrier's side members, a pair of crank arms secured to said transverse rod, links pivotally connected to the free ends of said crank arms and to said transverse bar, a second hand-lever secured to said rotatable rod for simultaneously disengaging said pawls from the ratchet teeth of the vertical members, in order to effect the lowering of said spaced rollers, pendant arms for contacting and releasing the locking levers of the cloth holders said pendant arms being pivotally secured to the carrier's sides one being adjacent each end of said carrier's sides, stops on said carrier's sides for limiting said pendant arms to movement in one, outward, direction only, and transverse rods secured between said carrier's sides, for contacting the tongues of said cloth holders and actuating same.

3. A cloth laying machine as claimed in claim 1, wherein the cloth holders at one end of the table are adjustably located on said table by clamping means which comprise a pair of transverse bars connected by plate members having depending portions in engagement with the rails at the sides of the table, a channel member secured between said pair of transverse bars for locating a slidable bar having a shoe on one end for engagement with a side of the table and a screw threaded portion at the other end, a second shoe for engaging the other side of the table and having an aperture for receiving the screw-threaded portion of said bar, and a nut lever for engagement with the screw thread of said bar, which nut lever when tightened engages the shoes with the table sides, and the bearings of the rotatable rod carrying said cloth holders being secured to one of said transverse bars.
